U. R. DENNISTON

HOT WATER HEATER

Filed April 28, 1926

18 Inventor,
Uriah R. Denniston,
by *Charles O. Sherry*,
his Atty.

UNITED STATES PATENT OFFICE.

URIAH R. DENNISTON, OF HAMMOND, INDIANA.

HOT-WATER HEATER.

Application filed April 28, 1926. Serial No. 105,094.

This invention relates to hot water heaters, and its principal object is to provide an apparatus having certain novel features for heating water with heat created by friction between relatively movable contacting discs. It has been proposed heretofore, to heat water with the heat created by the friction between stationary and movable discs, but the principal difficulty encountered in a device of this kind is the wear and tear on the discs, due to the excessive friction between them. One of the objects of the present invention is to provide a novel arrangement whereby a lubricant may be supplied to the discs so as to reduce the wear and tear thereon caused by the usual friction between the discs. Another object is to provide a hot water heater embodying a cylindrical casing having contacting stationary and rotatory discs therein and spaced away from the circular wall of the casing to leave a water heating chamber, and having an oil reservoir, and an oil pipe connecting the reservoir with the casing, whereby a body of oil may be maintained in said casing above the water level therein and in contact with the discs. The invention consists in several novel features hereinafter fully set forth and claimed.

20 The invention is clearly illustrated in the drawing accompanying this specification, in which:

Fig. 1 is a side elevation of a hot water heater embodying a simple form of the present invention; Fig. 2 is a view, partly in side elevation and partly in vertical section, of the hot water heater and showing fragments of a hot water heating system connected therewith; Fig. 3 is a vertical cross section of the hot water heater taken on the line 3-3 of Fig. 1; Fig. 4 is a detail cross section taken on the line 4-4 of Fig. 2; and Fig. 5 is a detail cross section taken on the line 5-5 of Fig. 2.

45 Referring to said drawing, which illustrates a simple embodiment of the present invention, the reference character 6 designates the casing of the heater which in the present instance comprises a circular wall 7, and two heads or side walls 8, 9. The casing is provided with a suitable base 10 which may be formed as a part of the wall 7. Conveniently the side walls 8, 9, may be made separate from the cylindrical wall 7 and may be bolted or otherwise secured thereto as is found desirable.

Journalized in bearings 11 mounted on the side walls 8, 9, is a drive shaft 12, which extends through the casing from side to side. The shaft may be driven from any suitable source of power and as shown it is driven from a motor driven shaft 13 journaled in bearing brackets 14, and having a worm pinion 15 secured upon it, which meshes with a worm gear wheel 16 keyed or otherwise secured to the drive shaft 12. The form of gearing just described is not material to this invention broadly considered, but is illustrative of one type of gearing which may be used satisfactorily.

50 Mounted on the shaft 12 within the casing 6 are rotatory discs 17, which are spaced apart and receive stationary discs 18 between them. The rotatory discs 17 are secured upon the shaft 12 by feathers, splines or the like 19, which are secured in key ways in the shaft 12 and enter notches formed in the rotatory discs 17. This arrangement is preferable since it permits the rotatable discs to be shifted along the shaft.

55 The stationary discs 18 are formed with centrally located openings 20, within which the shaft and its feathers or splines are free to rotate, and the said stationary discs are mounted upon rods 21 which are located in the annular space between the discs 17, 18 and the casing. The stationary discs may be formed with perforated ears or lugs 22 which receive the rods 21.

60 Means are provided for holding the discs in frictional contact with each other, and as shown a number of coiled compression springs 23 are employed for this purpose, which springs are contained in hollow bosses 24 and bear against plungers 25, which plungers bear against the adjacent or end-most stationary disc 18. The other ends of the springs 23 bear against threaded plugs or blocks 26 which are threadedly secured in the hollow bosses 24 and provide means for adjusting the tension of the springs 23 whereby more or less frictional contact between the discs may be obtained.

65 Adjacent the lower end of the casing 6 is a cold water inlet member 27 and at some point above the level of the cold water inlet member 27 is a hot water outlet member 28. From the hot water outlet member 28 leads the hot water pipe 29 of the system, which pipe may run to hot water radiators, a fragment of one of which is shown at 30, or it may lead to any tank or container which is to

be supplied with hot water. The cold water return pipe 31 from the system, connects with the cold water inlet member 27. As is usual in connection with hot water plants, 5 an overflow tank (not shown) is provided and an overflow pipe 32 may lead from some point in the system to the overflow tank.

The annular space between the casing and the discs 17, 18, comprises the heating chamber *a*, of the apparatus, and in the operation of the apparatus the discs 17 are rotated between the stationary discs 18, and the friction created between the discs is converted into the necessary heat for heating the 15 water passing through the heating chamber of the casing.

To prevent excessive wear on the discs, which would ordinarily occur without sufficient lubrication, I provide an oil tank or 20 reservoir 33 and connect it to the top of the casing 6 by an oil pipe 34. The oil tank or reservoir 33 is a closed tank and may contain a filler open at its top which is closed by a screw plug 35. In order to obtain 25 the best results, sufficient oil should be contained in the apparatus so that when in operation, a considerable portion of the upper halves of the discs will be above the lower level of the oil. This level is maintained by the water level which is illustrated by the dotted line 36. Above the water level 36 is an oil gauge or a drain cock 37 by which an attendant may ascertain when 30 the oil in the casing becomes less than is necessary for the perfect operation of the device, and this may be done by opening the oil gauge or drain cock, and if water escapes therefrom it is known that the oil in the tank or reservoir 33 should be replenished.

For the purpose of facilitating the lubrication of the discs, oil grooves or channels 38 may be formed in the sides of the discs, 45 preferably in the sides of the rotatory discs, which oil grooves open out through the edges of the discs and permit of the entrance of oil into the grooves, from which it is distributed along the faces of the adjacent discs during rotation of the rotatory 50 discs.

In the operation of the apparatus, rotation of the shaft 12 at a fairly rapid rate of speed, creates friction between the rotatory and stationary discs, and the discs 55 become hot as a consequence, which heat is conducted to the water contained in the annular heating chamber around the discs. The heated water circulates through the hot water system, as is well understood, and the cold water returns to the heater through the 60 return pipe 31. The oil being trapped between the water in the casing and the closed tank, presents a body of lubricating oil to the discs and lubricates them sufficiently to prevent 65 excessive abrasion, thereby prolong-

ing their lives without materially reducing the heating effect of the discs. Oil enters the grooves 38 of the discs and is distributed over the surface of the discs. As the oil disappears from usage the water level in the 70 casing rises and the attendant can determine when it is necessary to add a supply to the oil, by opening the drain cock 37. If water escapes it is known that the water level has reached a high point and that oil should be 75 added. By maintaining a body of oil for lubricating the discs the wear thereon is reduced to a minimum.

While I have described the invention in connection with a hot water heater, it may be used on a closed system for generating steam.

More or less variation of the exact details of construction is possible without departing from the spirit of this invention; I desire, therefore, not to limit myself to the exact form of the construction shown and described, but intend, in the following claims, to point out all of the invention disclosed herein.

I claim as new, and desire to secure by Letters Patent:

1. A friction heat apparatus, comprising in combination, a cylindrical casing having a cold water inlet and a hot water outlet, spaced discs stationarily mounted in said casing, a drive shaft journaled in said casing, spaced rotatory discs mounted on said shaft and extending between said stationary discs, pressure means applied to said discs, there being an annular heating space between the cylindrical wall of the casing and discs, an oil reservoir and an oil pipe connecting said oil reservoir with the annular chamber in said casing and arranged to constantly supply oil to said discs.

2. A friction heat apparatus, comprising in combination, a cylindrical casing having a cold water inlet and a hot water outlet, spaced discs stationarily mounted in said casing, a drive shaft journaled in said casings, spaced rotatory discs mounted on said shaft and extending between said stationary discs, pressure means applied to said discs, there being an annular heating chamber between the cylindrical wall of the casing and discs, a closed oil reservoir located above said casing, and an oil pipe connecting said oil reservoir with the heating chamber at the top of the casing and arranged to constantly supply oil to said discs.

3. A friction heat apparatus, comprising in combination, a casing having a cold water inlet and a hot water outlet, a drive shaft journaled in said casing, alternate stationary discs, stationarily mounted in said casing, and intermediate rotatory discs mounted on said drive shaft, pressure means applied to said discs for holding them in frictional contact, there being an annular heat-

ing chamber between the casing and discs, the major portion of which comprises a water chamber, and the upper portion of which comprises an oil chamber, an oil reservoir and a pipe connecting said oil reservoir with said oil chamber of the casing, whereby oil is supplied to said discs.

4. A friction heat apparatus, comprising in combination, a cylindrical casing having a cold water inlet and a hot water outlet, a drive shaft journaled in said casing, alternate stationary discs, stationarily mounted in said casing and coaxially with said shaft, said discs having central holes through which said shaft freely passes, intermediate rotatory discs mounted on said drive shaft, pressure means applied to said discs for holding them in frictional contact, there being an annular heating chamber between the casing and discs, the major portion of which

comprises a water chamber, and the upper portion of which comprises an oil chamber, an oil reservoir and a pipe connecting said oil reservoir with said oil chamber of the casing, whereby oil is supplied to said discs.

5. In a friction heat apparatus, a casing having a cold water inlet and a hot water outlet, alternate stationary and intermediate rotatory discs in said casing, and a drive shaft upon which the rotatory discs are slidably mounted, there being an annular chamber between the casing and discs for the reception of water and oil, and certain of the discs being formed with oil grooves in their faces, an oil reservoir and a pipe connecting said oil reservoir with the top of said annular chamber.

URIAH R. DENNISTON.
